(57) **CLAIM**

The ornamental design for a stemmed beverage glass drip catcher, as shown and described.

DESCRIPTION

FIG. 1 is a perspective view of a stemmed beverage glass drip catcher, showing my new design;

FIG. 2 is another perspective view thereof;

FIG. 3 is an enlarged perspective view thereof;

FIG. 4 is a front elevational view thereof;

FIG. 5 is a rear elevational view thereof;

FIG. 6 is a left side elevational view thereof; and

FIG. 7 is a right side elevational view thereof;

FIG. 8 is a top plan view thereof; and,

FIG. 9 is a bottom view thereof.

The broken lines in the drawing views represent unclaimed portions of a stemmed beverage glass drip catcher, which are included for the purpose of illustrating unclaimed environment, and portions of the article that form no part of the claimed design.
